UNITED STATES PATENT OFFICE.

WILLIAM M. KOONS, OF CHANUTE, KANSAS.

WINDOW SCREEN.

Application filed August 2, 1920. Serial No. 400,607.

To all whom it may concern:

Be it known that I, WILLIAM M. KOONS, a citizen of the United States, residing at Chanute, in the county of Neosho and State of Kansas, have invented a certain new and useful Improvement in Window Screens, of which the following is a specification.

My invention relates to improvements in window screens.

10 The object of my invention is to provide a window screen of novel construction which may be substituted for the ordinary extensible screen which is inserted in the window frame either below or above a sash, which may be easily extended or contracted as to width, so as to be easily inserted or removed, and which eliminates the break or joint in the netting such as is present in the ordinary adjustable screen.

20 My invention provides further a screen which is simple in construction, cheap to manufacture, durable and not liable to get out of order, and which may be readily inserted in or removed from operative position in a window frame by an unskilled person.

The novel features of my invention are hereinafter fully described and claimed.

25 In the accompanying drawing, which illustrates the preferred embodiment of my invention,

Fig. 1 is a perspective view of a portion of a window provided with my improved screen.

35 Fig. 2 is an enlarged view, partly broken away, showing the window frame in cross section and a top view of the screen, the latter being shown extended and locked in operative position.

40 Fig. 3 is a view similar to Fig. 2, the screen being shown contracted as to length.

Fig. 4 is a vertical sectional view on the line 4—4 of Fig. 3.

45 Similar reference characters designate similar parts in the different views.

1 designates a rectangular frame of the ordinary type, the opening of which is covered by an unbroken sheet of netting or screen wire 2.

50 One side edge of the frame 1 is beveled and designated by 3, said beveled edge being adapted to abut against and register with a beveled side edge 4 of a vertical end member 5 which is of substantially the same height as the frame 1 and which is hinged to the frame 1 so as to swing on a vertical axis

to and from a position in longitudinal alignment with the frame 1, the parts being shown in said position in Fig. 2.

For hinging the end member 5 to the frame 1, the following described means may be provided.

Two links 6 and 7 are mounted respectively in recesses 8 and 9, provided in the upper and lower ends of the end member 5. Two 65 screws 10 and 11 extend respectively through two slots 12 and 13, provided respectively in the links 6 and 7. The links 6 and 7 are respectively pivoted on two vertical screws 14 and 15, mounted respectively in 70 the upper and lower edges of the frame 1 adjacent to one end of the latter, said edges being respectively provided with recesses 16 and 17 in which are respectively mounted the links 6 and 7. 75

The member 5 is adapted to swing on the links 6 and 7 from the extended position shown in Fig. 2 to the position shown in Fig. 3. When in the latter position, the screen may be readily inserted between the stops 80 18 of a window frame 19 and under a sash 21, as shown in Fig. 1.

For releasably locking the member 5 in the extended position, there is pivoted to the inner side of the frame 1, a turn button 22, 85 which is adapted to be swung to and from a horizontal position in which it will overlap the inner side of the member 5, when the beveled edges 3 and 4 are in register and the member 5 is in longitudinal alignment with the frame 1.

23 designates a handle fastened to the inner side of the member 5. By turning the turn button 22 to the vertical position, and pushing outwardly on the frame 1, the end 95 member 5 and frame 1 may be swung to the position shown in Fig. 3, in which position, the screen may be readily removed.

To insert the screen in a window frame, the member 5 is swung into the position in 100 alignment with the frame 1 and between the stops 18, the frame 1 being between the opposite stops 18, after which the turn button 22 is turned to the horizontal position shown in Figs. 1 and 2, in which position it will overlap the member 5, thus holding the member 5 in the extended position.

By providing the beveled edges 3 and 4, there is no crack between the member 5 and the frame 1 when they are in the operative 110 position shown in Figs. 1 and 2, and the member 5 is permitted to swing laterally

outwardly on its axis. By having the member 5 hinged on a vertical axis, so as to swing laterally, the screen may be removed from the outside of the window without 5 having to lift the sash. This is a great advantage in case, as often happens, the sash has become stuck by paint in the frame. By having the beveled edges of the frame 1 and end member incline outwardly toward the 10 adjacent side of the window frame, as shown in Figs. 2 and 3, the joint between the frame and end member can not be broken by pushing inwardly from the outside of the window, thus making it difficult for an intruder 15 at the outside to remove the screen.

I do not limit my invention to the structure shown and described, as many modifications, within the scope of the appended claims, may be made without departing from 20 the spirit of my invention.

What I claim is:—

1. In a window screen, a netting carrying frame having a vertical beveled edge, an end member of the same height as the 25 frame having a vertical beveled edge arranged to register with the beveled edge of the frame when the latter and the end member are in the same vertical plane, and two links respectively pivoted on vertical 30 axes to the upper and lower ends of said

end member and respectively pivoted on vertical axes to the upper and lower edges of the frame, substantially as set forth.

2. In a window screen, a netting carrying frame having a vertical beveled edge, an end member of the same height as the frame having a vertical beveled edge arranged to register with the beveled edge of the frame when the latter and the end member are in the same vertical plane, two links respectively pivoted on vertical axes to the upper and lower ends of said end member and respectively pivoted on vertical axes to the upper and lower edges of the frame, and releasable means for holding the end member and the 40 frame in the same vertical plane, substantially as set forth.

3. In a window screen, a netting carrying frame, an end member, and a link pivoted on a vertical axis to the frame and pivoted to 50 said end member on a vertical axis.

4. In a window screen, a netting carrying frame, an end member, and a link pivoted on a vertical axis to said frame and slidably pivoted on a vertical axis to said end member. 55

In testimony whereof I have signed my name to this specification.

WILLIAM M. KOONS.
